UNITED STATES PATENT OFFICE.

JAMES ELLWOOD SANDERS, OF JERSEY CITY, NEW JERSEY.

DESIGN FOR A CHOCOLATE-MOLD.

SPECIFICATION forming part of Design No. 26,008, dated September 8, 1896.

Application filed February 3, 1896. Serial No. 577,936. Term of patent 14 years.

To all whom it may concern:

Be it known that I, JAMES ELLWOOD SANDERS, a citizen of the United States, residing in Jersey City, county of Hudson, and State of New Jersey, have invented a new and useful Improvement in a Design for Chocolate-Molds; and I do hereby declare that the following is a full, clear, and exact description of the same, reference being had to the accompanying drawing, forming part thereof, which represents in perspective a chocolate-mold of my design.

The leading feature of my design consists of a number of parallel ridges extending across the bottom of the mold from side to side and intersected by one or more like longitudinal ridges.

In the form of my mold represented in the

drawing, which shows part of the mold broken away to better reveal its design, the contour of the mold is rectangular and the inside of the mold flares upwardly. The bottom of the mold is formed of a series of transverse concave cylindrical segments parallel to each other and intersected at their middle by a longitudinal ridge of inverted-V-shaped form.

I claim as my invention—

The design for a chocolate-mold substantially as herein shown and described.

In testimony whereof I have hereunto set my hand the 6th day of September, 1895.

JAMES ELLWOOD SANDERS.

In presence of—

RICHARD WILLBURGER,
WM. H. WOODHULL.
